Robert H. Snyder.

By A. A. Barker, Atty.

UNITED STATES PATENT OFFICE.

ROBERT H. SNYDER, OF WORCESTER, MASSACHUSETTS.

ROLLING-MILL.

SPECIFICATION forming part of Letters Patent No. 679,919, dated August 6, 1901.

Application filed January 21, 1901. Serial No. 44,068. (No model.)

To all whom it may concern:

Be it known that I, ROBERT H. SNYDER, of the city and county of Worcester, in the State of Massachusetts, have invented certain new and useful Improvements in Rolling-Mills; and I do hereby declare that the following is a full, clear, and exact description thereof, reference being had to the accompanying drawings, forming a part of this specification, in which—

Figure 1 represents a plan, partly in section, of part of a bloom - rolling mill embodying my improvements. Fig. 2 is a vertical longitudinal section therethrough taken on line 15 $x x$, Fig. 1. Fig. 3 is a vertical transverse section taken on line $x' x'$, Fig. 1; and Fig. 4 is an enlarged vertical transverse section taken at the point indicated by line x^2 , Fig. 1, showing the parts to which my invention more particularly relate, as hereinafter more fully described.

The operation of rolling the ingots to the size of blooms is performed, as is well known, by passing said ingots back and forth longitudinally between the reducing-rolls, the ingots being turned one-fourth of a revolution by suitable automatic manipulators after each forward movement thereof preparatory to being passed back between said reducing-rolls for each succeeding reduction. During the first stages of reduction and until the ingot has been reduced to nearly the finished size the manipulators readily and properly turn it by catching under and raising one corner, which causes it to be turned one-fourth of a revolution, as aforesaid, and thus brings the opposite right-angle sides in position to come in contact with the reducing-rolls at the next passage therethrough, as usual; but when the reducing process has been nearly completed and the stock rolled down to nearly the finished size, preparatory to feeding it from the rolling-mill, more exactness is required of the manipulators in 35 catching under and turning the same on account of its smaller diameter, said manipulators being liable to come under the center instead of the edge of the ingot, and therefore lifting without turning it.

50 Heretofore it has been necessary for the attendants to assist the manipulators in turning the partially-reduced ingots by means of

tongs, owing to their increased length and pliability when thus reduced in size, the outer end being grasped in the tongs and turned as 55 the manipulators turn the inner end thereof.

The object of my invention is to overcome the foregoing objections in turning the ingot after it has been reduced to nearly the finished size, or, in other words, when said ingot has been reduced to so small a size as to be difficult to properly turn it by merely lifting one edge by means of the manipulators, as aforesaid. I accomplish said result by providing means for holding down the ingot 60 upon the side opposite from that upon which the manipulators act to lift and turn the same.

My invention consists in combining a series of projections or lugs with the inner vertical side of one of the stationary horizontal longitudinal side plates over the ends of the carrying-rolls of the mill for the purpose above described.

To enable others skilled in the art to which my invention appertains to better understand 75 the nature and purpose thereof, I will now proceed to describe it more in detail.

In the drawings, A A represent a pair of reducing-rolls, the parts B a series of carrying-rolls, and C C the stationary horizontal 80 longitudinal side plates above alluded to, upon the inner vertical side of one of which the aforesaid projections or lugs D are formed or secured, in this instance the same being shown riveted thereto. The parts E represent 85 the usual automatic manipulators, which have both vertical and horizontal movements imparted thereto by connection with suitable mechanism. (Not shown.) The purpose of said manipulators, it will be understood, is to 90 lift and turn and also to move the ingots laterally, as required, to bring them in line and also into the proper position for them to be passed between the reducing-rolls after each 95 passage therethrough and preparatory to the next passage between the same.

Assuming that an ingot has passed out from between the reducing-rolls A A onto the carrying - rolls B, the manipulators are then caused to be operated, all being operated together. They are first moved into position to bring one corner a of one of the forked upper ends E' under one edge of the bottom of said ingot. The manipulators are then ele-

vated, thus causing the ingot to be turned or tipped over one-fourth of a revolution into position for the next reduction. It is now, after having been thus turned, moved laterally in alignment with the proper place on the reducing-rolls for them to next operate upon it, after which it is passed longitudinally, as usual, between said rolls to reduce it in size, and so on, alternately operating upon said ingot until it is reduced to the desired size. After it has been reduced to so small a size as to make it difficult to readily and properly turn it by means of the manipulators alone, as above described, said operation may then be facilitated by means of the projections or lugs D on the inner vertical face of one of the longitudinal side plates C, previously described. In turning the partially-reduced ingot by the assistance of said projections or lugs it is first moved laterally, so as to bring the outer upper edge thereof under the projections or lugs, as is indicated by dotted lines F in Fig. 1. The manipulators are then adjusted to bring the corner *a* under the inner bottom corner thereof and elevated, thereby raising that side of the partially-reduced ingot G, as is shown in Fig. 4, and as its diagonally-opposite corner is held down by the projections or lugs D, as above described, said bloom must necessarily be turned or tipped over one-fourth of a revolution, or, in other words, to bring what was its inner vertical side at the top and its outer vertical side at the bottom. Having been thus turned, the manipulators are then operated to move it laterally into line for the next reduction, as also previously described. By the use of said projections or lugs D on the stationary side plates the

operation of turning the ingot, it is obvious, 46 is made positively certain, as it cannot be elevated without turning it. Considerable time is thus saved in the manipulation of the ingots in the process of reduction. This result has been fully demonstrated in practice in the manufacture of thousands of tons of blooms or slabs. 45

While my invention is very simple in construction and operation, the result thereby produced is of great importance in the manufacture of blooms, as a large saving is thereby effected not only in labor but expense in the manufacture of said product. 50

I have shown the projections or lugs D on only one of the side plates C; but it will of course be understood that they may be used upon both sides of the mill, if desired. To facilitate the operation of turning the ingot in case the forked ends of the manipulators do not catch under the bottom edge thereof, 60 the outer side of said forked end may be provided with a toothed or serrated edge *b*, as is shown in Figs. 3 and 4.

Having now described my invention, what I claim therein as new, and desire to secure 65 by Letters Patent, is—

In a rolling-mill, the combination with the stationary, horizontal, longitudinal side plate over the carrying-rolls, of a series of projections or lugs arranged in a horizontal line 70 upon the inner, vertical face of said side plate, for holding the outer, upper corner of the ingot in turning it by means of the usual manipulators, substantially as set forth.

ROBERT H. SNYDER.
